UNITED STATES PATENT OFFICE

WARREN M. OSBORN, OF CHICAGO, ILLINOIS

ROADBED

Application filed January 17, 1929. Serial No. 333,051.

The object of my invention is to provide a permanent road bed for railroad rails having a base, preferably of concrete, which may be made if desired in sections of standard rail 5 lengths, metallic stringers or sills embedded in the base and having rail-chairs permanently mounted thereon, and detachable insulating linings and rail-fastenings which may be easily assembled and readily renewed or re- 10 placed.

The invention consists in the arrangements and organizations of parts hereinafter described and pointed out in the appended claims.

15 In the accompanying drawings, which illustrate practical embodiments of the features of my invention and in which the same reference numerals in the different views indicate the same or like parts, Fig. 1 is a plan view 20 of a section of a railroad bed of any standard rail length constructed in accordance with my invention, and with a pair of rails in place; Fig. 2 is a side view of the same; Fig. 3 is a central longitudinal sectional view on the 25 line 3—3 in Fig. 1; Fig. 4 is a cross-sectional view in part on the line 4—4 in Fig. 5 on an enlarged scale; Fig. 5 is a detail longitudinal sectional view on the line 5—5 in Fig. 4 on similar scale; Fig. 6 is a perspective side view 30 of a rail-wedge; Figs. 7 and 8 are detail views showing a rail-chair; Fig. 9 is a detail side view with the bottom of a rail-chair in section; Fig. 10 is a detail top plan view, and Fig. 11 is a detail cross-sectional view of a portion 35 of the bed with a rail in place.

In practicing my invention I employ parallel pairs of rail stringers or sills extending longitudinally of the track gauge, and formed preferably of suitable metallic 40 I-beams which have their webs 25 somewhat expanded vertically to afford increased depth between their top and bottom flanges 26 and 27, and provided with transverse openings as shown generally in Fig. 5. These longitudinal beams are connected at intervals by cross-girders consisting of relatively short I-beams approximating in length the gauge of a track and formed with their webs 29 expanded vertically and their top and bottom 45 flanges 30 and 31 respectively fitting between the flanges of the longitudinal beams and fastened thereto at their ends by suitable means, preferably by welding the parts together as indicated at 28. The webs 25 are connected, preferably just below the flanges 55 26, by cross-rods 32 at intervals secured by nuts 33 threaded on their ends, and rail-chairs 34 are welded to the flanges 26 as indicated at 35. The longitudinal beams and cross-girders are embedded in a base 36, preferably 60 formed of concrete, and provided with longitudinal and transverse reinforcing rods 37 and 38 respectively, and passing through the openings in the webs of the stringers and cross-girders. The concrete may be poured 65 into molds or forms of desired outline after the above parts are assembled in place in track, or it may be pre-cast in slabs of any predetermined rail-lengths either for single or double tracks with the above parts in place. 70 The forms are constructed to provide track-gauge grooves 39 in the top of the base 36 above the flanges 26 and between the rail-chairs and in general slightly wider than the rail-bases, and insulating and sound-deadening strips 40, preferably of asphaltic or rubber composition, are seated in the grooves 39 75 between the rail-chairs; these strips are preferably trough-shaped in cross-section with their sides 41 extending in position along the 80 edges of the bases of the associated rails 42 as shown in Fig. 11. The rail-chairs 34 preferably have channels 43 in their bases forming seats for insulating and sound-deadening pads 44 as shown in Figs. 7 and 8. The strips 85 40 and the pads 44 are formed and arranged so that their ends abut and their top surfaces are flush as shown generally in Figs. 9 and 10, so that the rails are supported throughout 90 their length on insulating and sound-deadening material. The inner faces of the sides of the chairs are preferably concave or curved, as shown at 45 in Figs. 7 and 8, and are angular to each other to form tapered seats for insulating and sound-deadening elongated 95 rail-fastening wedges 46, which conform to the contours of assembled rails and chair-sides, and are driven into place between them with their ends projecting beyond the ends of 100 the chair-sides.

In practice the stringers and cross-girders are assembled in a suitable form or mould and connected together with the stringers spaced in track-gauge, the rail-chairs are welded to the flanges 26 at intervals in track-gauge, the cross-rods 32 and the reinforcing rods 37 and 38 are assembled in place, and the concrete is poured; usually the concrete is formed in slabs of say thirty-nine (39) feet in length and say ten (10) feet in width and say twenty (20) inches in depth, in which case the cross-girders are say twelve (12) feet between centers and arranged in general as shown in Figs. 3 and 4. After the concrete sets and such parts (at least) of the form as make the grooves 39 are removed, the strips 40 and pads 44 as assembled in place, the rails are laid and the wedges are driven to place. The rails are thus fastened to the stringers independently of any bolt or clip connections, are protected at their fastenings and supported throughout their lengths by insulating and sound-deadening linings, and the entire rail-carrying structure is welded together into a unit and embedded in a base which resists the weight and stresses of traffic and prevents rail creeping and insures permanent track-gauge. The strips 40 and pads 44 are preferably resilient to prevent the metallic stringers and chairs from crystallizing and being crushed under the action of the rails under traffic. The rails are automatically gauged in track when assembled in their chairs, and they can be changed by merely removing the wedges, and the protective lining material can be renewed by merely lifting the rails. The wheel loads on the rails are uniformly distributed over the entire length of the stringers and cross-girders, and these are held in gauge in the base. No ballast is required, and the cost of tamping and packing it is saved; the usual settling of ties with consequent danger of throwing the track out of gauge and necessity for periodic tamping of ballast is obviated. The slab may be provided with grouting pipes 47, and with inclined cross-drains 48 having discharge pipes 49.

I claim:

1. A rail bed for railways comprising a permanent base provided in its top surface with parallel rail-grooves in track gauge, metallic stringers embedded in said base and forming the lower walls of said grooves, rail-chairs in said grooves permanently mounted on said stringers, insulating linings in said chairs and grooves, and insulating rail-fastenings in said chairs on both sides of associated rails.

2. A rail bed for railways comprising a permanent base provided in its top surface with parallel rail-grooves in track gauge, expanded I-beams embedded in said base with their top flanges forming the lower walls of said grooves, rail-chairs in said grooves welded to said flanges, insulating linings in

said chairs and grooves, and insulating rail-fastenings in said chairs on both sides of associated rails.

3. A road bed for railways comprising a rectangular concrete slab having its length substantially equal to a standard rail length and its width exceeding standard track-gauge and provided in its top surface along its length with parallel rail-grooves in track-gauge, I-beams and cross-girders tied together in unitary form and embedded in said slab, the top-flanges of said beams forming the lower walls of said rail-grooves, rail-chairs in said grooves welded to said flanges and having channels parallel therewith, insulating and resilient linings in said grooves and channels forming rail-seats, and insulating wedges in said chairs on both sides of the rails on said seats.

4. A road bed for railways comprising a rectangular concrete slab having its length substantially equal to a standard rail length and its width exceeding standard track-gauge and provided in its top surface along its length with parallel rail-grooves in track-gauge, expanded I-beams and cross-girders welded together in unitary form and embedded in said slab, the top-flanges of said beams forming the lower walls of said rail-grooves, rail-chairs in said grooves welded to said flanges and having channels parallel therewith, insulating pads in said channels, insulating strips in said grooves between adjacent chairs and forming with said pads resilient rail-seats, and insulating wedges in said chairs on both sides of the rails on said seats.

5. A rail bed for railways comprising a permanent base provided in its top surface with parallel rail-grooves in track-gauge, metallic stringers embedded in said base and forming the lower walls of said grooves, rail-chairs in said grooves permanently mounted on said stringers, asphaltic strips in said chairs and grooves, and insulating and sound-deadening rail-fastenings in said chairs on both sides of associated rails.

In testimony whereof, I have hereunto subscribed my name.

WARREN M. OSBORN.
